Perley Sherman
ATTORNEY

UNITED STATES PATENT OFFICE

ABRAHAM POSNER, OF BROOKLYN, NEW YORK

ORTHOPEDIC SHOE

Application filed January 22, 1930. Serial No. 422,581.

This invention relates to orthopedic shoes for all persons of any age whereby malformations of the feet may be prevented and even corrected without discomfort.

5 The key-stone bone of the foot is the os calcis. Changes in the axial alignment of this bone will secondarily involve the other bones of the foot and disrupt its integrity as a weight bearing organ.

10 Attached by ligaments to the os calcis is the bone immediately on top of it and anterior to it known as the astragalus. It is on top of this astragalus that the tibia and fibula bones of the leg rest. Immediately adjacent 15 to the astragalus and forward thereof on the inner side of the foot is the scaphoid. The so called longitudinal arch of the foot that is on the inner side of the foot is formed by this archway underneath the astragalus and 20 scaphoid bones and by the internal cuneiform bone and first metatarsal bone.

The normal function of the foot based on a proper tread of the os calcis will cause the forepart of the foot to tread straight ahead 25 slightly inclined inward. The weight bearing is on the outer side from the heel to the ball and is accentuated on the outside or outer border of the os calcis. This is often reflected in a wearing down of the surface of 30 the heel of the shoe on the rear side of the heel.

Pronation or a tendency towards weak foot is very common with children, and of course weak foot or flat foot conditions are 35 also prevalent with grown ups. However, this tendency towards pronation or weak foot is evidenced by a rotating outward of the heel bone or oscalcis resulting in a secondary motion, that of the astragalus and scaphoid

40 rotating downward and inward and consequently throwing the forepart of the foot outward instead of straight ahead with an inclination inward. To relieve this condition or prevent pronation or a tendency toward 45 weak foot, the introduction of a wedge of a

thickness proportionate to the degree of pronation is inserted in the inner border of the heel. This wedge has a tendency to lift up the inner part of the os calcis, straightening it out and thus avoiding the rotation outward of the os calcis when the os calcis is brought in this straight alignment position, the astragalus and scaphoid assume their correct positions and the forepart of the foot treads straight with a tendency inward as 55 it properly should.

If this so-called balance or uniformity could be maintained merely by the introduction of a wedge as outlined above, the difficulty would be overcome but, as noted above, 60 the natural tendency is to walk on the outer surface of the heel. By the introduction of the wedge, this weight bearing on the outer side is more accentuated and if carried to extreme, that is to say, if excessive wedging 65 is provided, to wit: to a degree greater than in the degree of so-called supination, the opposite is likely to occur. Accordingly, it becomes necessary to introduce in the outer tread surface of the heel, a substance of 70 greater durability than leather which will offset the tendency to wear down the outer side of the heel, thus bringing about a uniformity in wear. The introduction of this substance in addition to maintaining this uniformity of 75 wear and preventing excessive correction also has a tendency of establishing a line of resistance throwing the said balancing to the outer side of the heel where it belongs. It is to be borne in mind when we refer to the wearing down of the shoe on the outer side of the heel that what is really meant is wearing down toward the outer side of the back of the heel.

The introduction of this substance on the 85 outer side of a durability greater than that of leather bringing about a uniformity of wear of the heel will help to maintain the same degree of wedging from the first day a person wears the shoe until and through the life of 90

the corrective feature of the shoe. In other words there is avoided the tendency of the degree of correction changing after the shoe is worn when this re-enforcement is put into the shoe.

Hence, one of the objects of the invention is to provide a shoe in the structure of which is incorporated scientific means to cause the heel to assume its natural physiological position if the feet be weakened or abnormal; or to prevent the development of such conditions if the feet are normal, and in combination therewith to provide reinforcement for the rear outer tread surface of the heel of the shoe to retard wear thereon and thus maintain uniformity of wear on the entire heel tread.

A further feature is in the provision of means to support the tarsal bones and joints without interfering with the desirable flexibility of the shank of the shoe.

Another purpose is to produce a shoe having a permanent support for the natural development and functions of the metatarsal arch, but without disfigurement or noticeable change from the usual appearance of the shoe.

These important purposes are accomplished by the novel construction and combination of parts constituting the structure of the shoe as hereinafter described and shown in the accompanying drawings complementary to the description, and in which:

Fig. 1, is a perspective view of a shoe for youths made in conformity with the invention.

Fig. 2, is an enlarged partial bottom plan view of a shoe as seen during construction, parts being broken away to show the same.

Fig. 3, is a perspective view showing the supporting element in detail.

Fig. 4, is a fragmentary longitudinal sectional view of the sole elements, the section being taken on line 4—4 of Fig. 1.

Fig. 5, is a rear elevational view of the shoe with heel attached.

Fig. 6, is a side elevational view of a shoe for young children embodying the invention.

Fig. 7, is a bottom plan view of the same, part of the sole being broken away, as in Fig. 2.

The shoe shown in Figs. 1 to 5 consists of the usual uppers 10, vamp 11, outer sole 12 and heel lifts 13 on the sole.

An insole 14 is extended the entire length of the shoe and intermediate the soles 12 and 14 is a comminuted cork insert or filler 15 reaching from the toe to a point below the instep where it adjoins a filler strip 16 of leather extending to the forward edge of the heel.

Another insert 17, shown in detail in Fig. 3, is composed of a strip of leather having its outer edge 18 curved in conformity with the contour of the heel and an inner straight edge 19 skived to a feather thickness, as at 20, and disposed so as to cover over half of the width of the heel, directly upon the inreaching at-

tached edges of the upper and sole 14 as best seen in Fig. 2.

Extending forwardly from the offset 21 of the heel portion 20 of the insert is an integral strap element 22, reduced in thickness and disposed over the filler strip 16 to which it is cemented.

The filler 16 is skived from the centre, transversely of the shoe, to feather edges and its purpose is to permit full flexation of the shoe when walking.

A support pad is continued from the concavely skived strap, the same being disposed in a recess 25 formed by the filler 15 and insole 14, one edge of the pad being a continuation of the straight edge 19 and the thickness of the pad is preferably slightly in excess of the filler 15, as best seen in Fig. 4, its disposition being directly below the shanks of the second, third and fourth metatarsal bones.

When the heel lifts 13 are secured in place on the shoe the rear portion 20 of the element tilts the heel in the desired manner as shown in Figs. 1 and 5.

In the top lift of the shoe, as seen in Figs. 1 and 5 are inserts 26 of fibre or other hard wearing material and these inserts or plugs may be inserted in a counterbore in the top lift before it is attached to remainder of the heel.

The infant's shoe, seen in Figs. 6 and 7, is substantially of like construction, with the exception that the outer sole 12' is extended to contact directly with the surface trodden upon by reason of its being applied over the unitary support elements 20'—22'—23', and the heel extended downwardly on a slight bevel formed by skiving its forward portion.

While certain preferred embodiments of this device have been shown and described, it will be understood that changes in the form, arrangements, proportions, sizes and details thereof may be made without departing from the scope of the invention as defined in the appended claims.

Having thus described my invention, what I claim as new and desire to secure by Letters Patent, is:

1. An orthopedic shoe having inner and outer soles, a flexible cushion pad therebetween at the forward part of the shoe, a heel, a wedge-shaped element combined therewith at the inner side of the shoe, a flexible strap extending forwardly from said element centrally of the shoe, and a metatarsal support at the end of the said strap entering a recess in said pad below the second, third and fourth metatarsal bones.

2. An orthopedic shoe having inner and outer soles, a flexible cushion pad therebetween at the forward part of the shoe, a heel, a wedge-shaped element combined therewith at the inner side of the shoe,

flexible strap extending forwardly from said element centrally of the shoe, said strap presenting a concave upper surface, a transverse plate fixed thereon to seat against the inner sole, and an elongated element integral with said strap, and wedge-shaped element, to extend into a recess below the second, third and fourth metatarsal bones.

Signed at New York, in the county and State of New York, this 24th day of December, 1929.

ABRAHAM POSNER.
